UNITED STATES PATENT OFFICE.

WILLIAM W. ROSENFIELD, OF NEW YORK, N. Y.

COIN-CONTROLLED STRENGTH-TESTING MACHINE.

No. 796,358.

Specification of Letters Patent.

Patented Aug. 1, 1905.

Application filed May 28, 1903. Serial No. 159,078.

To all whom it may concern:

Be it known that I, WILLIAM W. ROSENFIELD, a citizen of the United States, residing in the borough of Manhattan, in the city, county, and State of New York, have invented an Improvement in Coin-Controlled Strength-Testing Machines, of which the following is a specification.

My invention relates to a coin-controlled machine adapted for testing the human strength in which a common instrumentality is actuated both by an upward-pulling position of the body and also by an approaching movement of the hands operating separate devices. These movements are independent of one another, and each separately indicates on a common instrumentality the force employed.

In the operation of my improved testing-machine and when either hand-moved instrumentality is brought into play after a coin of predetermined denomination has been inserted the force applied moves a rod and head downward against the expansive action of a spring. This head carries an arm adapted to bear upon the coin inserted in the machine, which when moved down carries with it a sliding block actuating a rack and pinion, the pinion-shaft, and index to show the force applied. A friction-clutch device is employed to hold these latter devices in their extreme position until released after the return of the first-named means to their normal position, and I provide suitable devices adapted to prevent the fraudulent use or repeating with the machine with a single inserted coin, all of which are hereinafter more particularly set forth.

In the drawings, Figure 1 is a front elevation of my improved coin-controlled strength-testing machine. Fig. 2 is a side elevation, a part of the base being broken away. Fig. 3 is an elevation of the case and internal mechanism with the dial, front plate, and handles removed and the shafts of the handles and index in section and one guide-rod broken away. Fig. 4 is a side elevation with part of the case and certain other parts in section. Fig. 5 is a vertical section and elevation of the coin receiving and engaging devices. Fig. 6 is a sectional plan at $\pi\pi$ of Fig. 4, and Fig. 7 is a central elevation at the back with the rear plate removed.

a represents the hollow base of the machine, with which is made a platform a' to stand upon. At the back of the hollow base rises a standard b , the main case c being mounted upon the standard b and provided with an aux-

iliary or back case c' . At the forward portion of the hollow base there is an auxiliary standard b' .

d represents the dial upon the face of the case c at the upper end, 2 the index or hand to indicate the force applied, and 3 represents the coin-slot.

A hand-bar d' is upon the upper end of a rod g , that passes down through the auxiliary standard b' . In the hollow base there is a lever g' , pivoted at 4 to said base. This lever, as seen in Fig. 2, is slotted at the left-hand end to receive a pin which passes through the rod g and is the means for connecting said rod g and the lever g' , the pin moving in the slot with the change of position of the parts. The right-hand end of the lever g' is provided with an opening to receive the main rod h , which passes through it, as well as through the hollow base a , and in the end of the rod h is a pin coming below the end of the lever g' . e, f represent the hand-levers. These are outside of the case c and at opposite sides. They are connected to shafts e', f' , which pass through lugs at the sides of the case and the ends of which shafts pass inside of the auxiliary or back case c' and terminate in arms e^2, f^2 .

The main rod h passes up into the auxiliary or back case c' and through limiting-stops on the back of the case c . A helical spring h' , with washers at the respective ends of the spring, surrounds the main rod h between these stops 5, 6, and there is a pin h^2 through the rod h beneath the stop 6 and above the adjacent washer. At the upper end of the rod h is a head i , having a forward-extending arm i' passing through a mortise in the back of the main case and which head is also provided with side extensions slidable against the ways a^2 on the back of the case c . Fig. 7 shows the normal position of the hand-lever shafts and their arms e^2, f^2 , in which the free ends of the arms, which lap one another, are directly over the center of the head i and come below a lug 19 of the case c , which by holding down the arms e^2, f^2 prevent a swinging or overbalancing movement of the hand-levers e, f .

I provide guide-rods 7, 8, occupying a plane parallel to the front of the case. The upper ends of these rods are secured to the top of the case and their lower ends to a bracket 9, secured to and projecting from one side of the case. These rods 7, 8 become guides for the slidable block k . This block is of pecul-

iar shape, (see Figs. 3, 4, 5, and 6)—that is to say, it is made with portions through which the rods 7 8 pass. It is provided with a coin-slide k' , notched at its lower end and formed between parallel ribs. (See Fig. 6.) There is a block 10 adjacent to the upper ends of the guide-rod 7 8 and through which they pass, which block is held to said guide-rod by a screw and a tension-spring 11 at its upper end is hooked onto this screw or tap-bolt, and the lower end of this spring 11 is secured to a clamping-screw 12, which passes through the slidable block k , the said screw 12 firmly connecting the rack-rod l to the slidable block k . This rack-rod is preferably round, and the teeth forming the rack are cut into one side of the same, said rack-rod being guided in the block 10.

The shaft m passes through the upper end of the case c , its rear end having a bearing in the back of the case and its forward end a bearing at the center of the dial. The forward end of the shaft carries the index 2, and upon this shaft m is a pinion m' , meshing with the teeth of the rack-rod l , so that by the up-and-down movement of the rack-rod the pinion m' , shaft m , and index 2 are rotated. On the shaft m and at the back portion is a hub m^2 , and pivoted to a boss 13 upon the back of the case is an arm n , said arm moving on the pivot 14, secured to the boss 13. The arm n is made with a friction-ring n' surrounding the shaft m and adapted to bear upon the face of the hub m^2 of the shaft m . To this arm n at the lower end is connected a push release-pin n^2 , the same being pivotally connected at one end to said arm and extending through the front of the case and slightly beyond the same, so as to be manipulated by hand. A spring 15 is located between the front of the case and the arm n , one end of the spring being connected to an eylug of the case and the other end to an eylug of said arm, the function of the spring being to draw the lower end of the arm toward the front case and apply friction between the friction-ring n' and the hub m^2 to prevent the shaft m and the parts associated therewith from being moved.

I provide a follower o in the form of a block having apertures through which pass the rods 7 and 8 and having an inclined part generally parallel with the inclined coinway part of the slidable block k . The end of this inclined part is notched, and on the under side there are lugs 16 and at one side an adjusting-screw 17, Figs. 5, 6. The notched portions of this inclined follower and the inclined part of the slidable block k receive the free end of the arm i' , the face of which is inclined so as to be parallel with the inclined portion of the block k , and it is apparent that it is possible with the vertical movement of the rod h , either by means of the hand-levers $e f$ or the hand-bar d' , for the free end of the arm i' to pass through

these notches of the slidable block k and the follower o , providing there is no intervening coin. This follower o is provided with a vertical face o' , hereinafter more particularly described. On the left-hand side of the case (see Fig. 3) there is a bracket 18, providing a bearing for the pivoted rack r , which hangs normally by gravity from its connection with said bracket and which rack is provided with an arm r' and which arm r' extends across over the free end of the arm i' .

The operation of the machine is substantially as follows: The coin is inserted into the machine through the coin-slot 3. This coin may be a nickel or a cent. In either case the slide-way k' between the side ribs of the slidable block k is wide enough for the coin. If a nickel, the coin stops against the side lugs 16. If a cent, the same stops against the screw 17 and one lug 16. If now a person testing his strength grasps the hand-bar d' , standing on the platform d' , and pulls upward, the lever g' is swung on its pivot 4 and the main rod h is drawn down against the tension of the spring h' . The spring is compressed, and in drawing down the rod the head i and arm i' are simultaneously moved. The arm i' comes against the coin with the initial movement of the parts, and through the intervention of the coin the arm i' moves downward the slidable block k , the rack-rod l straining the tension-spring 11, turning the pinion m' , the shaft m , and the index 2 so long as the downward movement of the rod h continues.

It will be noticed that the arm r' of the rack r extends above the free end of the arm i' and in the position Figs. 4 and 5 substantially rests on this arm, so that the rack r is held away from the lug k^2 on the side of the slidable block k , but when this arm i' moves down the said rack hangs by gravity, and as the lug k^2 moves downward with the slidable block k the same runs over the surface of the teeth of the rack r , and when the limit of this movement is reached the teeth of the rack close over the lug preparatory to holding the same in position. Simultaneous with this movement the grip of the pivoted arm n and friction-ring n' against the hub m^2 of the index-shaft is in evidence to hold the parts in the position reached by the pressure or the force applied by the person testing his strength. The moment that this pressure is released the spring h' acts to return the rod h , the lever g' , the rod g , the hand-bar d' , the head i upon said rod, and the arm i' to their normal or initial position. As the arm i' starts upward the coin is released and falls into a coin-box s , suitably supported in the machine.

The frictional grip in evidence through the intervention of the arm n and the parts associated therewith remains to maintain the index in the position to which it has been brought. The rack r also engages the lug k^2 while the arm i' is moving upward; but before

this arm i' reaches its normal position it engages the arm r' of the rack and swings the rack free from the lug k^2 , so that were it not for the friction-grip of the arm n and the parts associated therewith the spring 11 would at once return the slidable block k to its original or initial position preparatory to a repetition of the aforesaid movements. In connection with this movement the hand-levers e, f and the parts associated therewith to and including the arms e^2, f^2 are not moved at all, because the free ends of these arms e^2, f^2 come above the head i , (see Fig. 7,) and they are not affected by the downward movement of the head i and rod h . If a person testing his strength operates the hand-levers e, f , the free ends of the arms e^2, f^2 are brought with force on the top of the head i to force down the rod h against the expansion of the spring h' , and in doing this the arm i' is after the insertion of the proper coin brought against the coin, so as to force down the slidable block k and repeat the operations hereinbefore described and indicate a force applied upon the dial. In this latter movement the arm h at its lower end moves freely through the eye at the end of the lever g' , so that this lever, the rod g , or the hand-bar d' are not in any sense affected or moved. The relation of the respective forces applied as between the hand-bar d' and the hand-levers e, f and indicated on the scale is such that the force indicated by the hand-bar d' can be read as indicated, but the indication produced by the operation of the hand-levers e, f should be divided in two to arrive at substantially the exact force applied.

With either operation and after the release of the hand-bar d' or the hand-levers e, f the push release-pin n^2 is to be forced into the case to overcome the tension of the spring 15, swing the arm n , and release the frictional hold of the ring n' and hub m^2 . This frees the shaft m and permits the tension-spring 11 to act to draw upward the slidable block k and rack l , and so rotate the pinion m' and shaft m , returning the index 2 to the zero-mark ready to repeat the operations.

It will be noticed that the follower o is provided with a vertical face o' and a side lug o^2 , and this face o' moves in a plane parallel with the plane of the front of the case and in its limited descent passes across the coin aperture or slot 3 and in the movement of the parts will prevent the insertion of another coin, because this follower o only descends until the side lug o^2 strikes the corner-shoulder of the bracket 18, which assists its movement and suspends the said follower upon the guide-rods 7 and 8, with its vertical face o' closing the coin-slot and preventing the insertion of another coin until all the parts are raised to their normal position, the latter part of the movement of which raises the follower to the position shown in Fig. 5.

The main function of the rack r , pivoted to the bracket 18 and its arm r' , is to prevent fraudulent repetition or beating of the machine, as it will be noticed from the drawings and the foregoing description that this rack engaging the lug k^2 positively holds down the slidable block k at the position reached until almost the end of the return movement of the arm i' . Should an attempt be made, as an illustration, by some one engaging the hand-bar d' to test their strength immediately following the test of some one operating the hand-levers e, f , or vice versa, or should some one desire to test his strength several times in succession it is necessary in all cases that an effort be made with the movement of the parts to maintain the coin in the coinway and gripped between the same and the inclined forward edge of the arm i' . To accomplish this the friction device must be released by operating the push release-pin n^2 , so that the contractile action of the spring 11 will tend to raise the slidable block k , and so hold the coin between the same and the end of the arm i' . Under these circumstances were it not for the rack r and the lug k^2 on the side of the slidable block k a fraudulent repetition or beating of the machine might be effected; but it will be apparent that the presence of these devices in the machine makes this action impossible, because the moment that the arm i' passes down below the gravity position of the arm r' the said rack r is effective for engaging the lug k^2 to hold the slidable block k to whatever position the extreme downward movement has carried it.

I claim as my invention—

1. In a coin-controlled machine, the combination with an indicating device and means associated therewith for actuating the same, of separate independent manually-operated devices and devices separate therefrom and independently actuated by either of the manually-operated devices, the one moving the other only upon the introduction and interposition of a coin between the parts and with which coin they forcibly contact, the thrust of the parts thereon being employed for operating the indicating device.

2. In a coin-controlled machine, the combination with a vertically-movable spring-controlled rod, of separate manually-operated devices adapted to independently actuate said rod, devices for receiving an inserted coin, devices connected to said rod and adapted to engage said coin, and means connected to the coin-receiving devices for indicating the applied pressure and for returning the parts to a normal position.

3. In a coin-controlled machine, the combination with an indicating device and means associated therewith for actuating the same, of separate manually-operated devices and devices independently actuated thereby for operating the indicating device upon the inser-

tion of a coin, spring-controlled devices for producing a holding friction available for maintaining the index at the position of extreme movement, and other devices simultaneously holding the said index-actuating devices for preventing the fraudulent use or repeating of the instrument.

4. In a coin-controlled machine, the combination with an indicating device, and means associated therewith and for actuating the same, of a coin-receiving device, a vertically-movable spring-controlled rod and an arm connected therewith adapted to engage or contact with the coin upon the coin-receiving device, a pair of hand-levers and their shafts, and arms on the opposite ends of said shafts extending toward one another and above the upper end of the said spring-controlled rod for actuating said rod with the movement of the hand-levers.

5. In a coin-controlled machine, the combination with an indicating device and means associated therewith and for actuating the same, of a coin-receiving device, a vertically-movable spring-controlled rod and an arm connected therewith adapted to engage or contact with the coin upon the coin-receiving device, a pivoted lever in the case of the coin-controlled machine at one end engaging the lower end of said spring-controlled rod, and at its other end engaging a vertically-movable rod and a hand-bar at the upper end of the vertically-movable rod.

6. In a coin-controlled machine, a slidable block and vertical guides therefor, said block having a coin way or slide receiving and down which the coin moves, lugs for arresting a coin of a given denomination, an adjusting-screw for arresting a coin of a different denomination, an indicating device, means associated therewith and connected also to the slidable block, and manually-operated devices adapted to engage the coin and actuate the slidable block and the parts intervening between the same and the index.

7. In a coin-controlled machine, a slidable block and vertical guides therefor, said block having a coin way or slide receiving and down which the coin moves, lugs for arresting a coin of a given denomination, a device normally resting upon the slidable block and to which is connected the said coin-arresting lugs, said device having a vertical face and a limited vertical movement, said face at the end of said movement covering the coin-slot and preventing the insertion of a second coin until the movements have been completed.

8. In a coin-controlled machine, a slidable block and vertical guides therefor, said block having a coin way or slide receiving and down which the coin moves, lugs for arresting a coin of a given denomination, a device normally resting upon the slidable block and to which is connected the said coin-arresting lugs, said device having a vertical face and a

limited vertical movement, said face at the end of said movement covering the coin-slot and preventing the insertion of a second coin until the movements have been completed, an indicating device, means associated therewith for actuating the same, a connection from the latter means to the slidable block, and a spring for returning the parts to their normal position.

9. In a coin-controlled machine, a slidable block and vertical guides therefor, said block having a coin way or slide receiving and down which the coin moves, lugs for arresting a coin of a given denomination, a device normally resting upon the slidable block and to which is connected the said coin-arresting lugs, said device having a vertical face and a limited vertical movement, said device at the end of said movement covering the coin-slot and preventing the insertion of a second coin until the movements have been completed, an indicating device, means associated therewith for actuating the same, a connection from the latter means to the slidable block, a spring for returning the parts to their normal position, and a spring-controlled friction device acting upon the means associated with the indicating device for holding the same at the end of their indicating movements, and which friction devices are manually released to permit the aforesaid spring to return the parts to their normal position.

10. In a coin-controlled machine, a slidable block and vertical guides therefor, said block having a coin way or slide receiving and down which the coin moves, lugs for arresting a coin of a given denomination, a device normally resting upon the slidable block and to which is connected the said coin-arresting lugs, said device having a vertical face and a limited vertical movement, said face at the end of said movement covering the coin-slot and preventing the insertion of a second coin until the movements have been completed, an indicating device, means associated therewith for actuating the same, a connection from the latter means to the slidable block, a spring for returning the parts to their normal position, a pivoted gravity device adapted to engage said slidable block at its extreme movement and to hold the same and the parts connected therewith and extending to the indicating device for a predetermined period.

11. In a coin-controlled machine, the combination with an indicating device, means associated therewith for actuating the same, of separate manually-operated devices, a vertically-movable spring-controlled rod independently actuated by either of said manually-operated devices, a vertically-movable coin-receiving device, an arm connected to the upper end of said spring-controlled rod extending toward said coin-receiving device and adapted to contact with the coin therein, a rack and an arm connected to said rack pivotally mounted

in a bracket of the case and hanging by gravity, lugs upon the coin-receiving device adapted to be engaged by said rack to hold the coin-receiving device in the extreme position to which the same may be carried during the major portion of the return movement of the arm connected to the spring-controlled rod, and which arm, at the end of its movement, contacts with the arm of said rack to release the hold of said rack and permit the coin-receiving device to return to its initial position.

12. In a coin-controlled machine, the combination with an indicating device, means associated therewith for actuating the same, of separate manually-operated devices, a vertically-movable spring-controlled rod independently actuated by either of said manually-operated devices, a vertically-movable coin-receiving device, an arm connected to the upper end of said spring-controlled rod extending toward said coin-receiving device and adapted to contact with the coin therein, an arm pivoted to a bracket of the case, spring-controlled and having a part surrounding the shaft of the index, a device upon the said shaft contacting frictionally with the aforesaid part of said arm for producing a friction to hold the index, the parts connected therewith and the vertically-movable coin device in the extreme position to which the same may be moved, and a push release-pin connected to the opposite end of said pivoted arm and extending through the case for releasing the frictional hold thereof to permit the parts to return to their initial position.

13. In a coin-controlled machine, the combination with an indicating device, means associated therewith for actuating the same of a coin-receiving block having divided inclined ways, a follower device also having inclined divided parts, lugs on the under side and an adjusting-screw on the one part adapted to act upon coins of different denominations, manually-operated devices, a spring-controlled rod actuated thereby, an arm extending forward of the spring-controlled rod and entering the notch or space between the divided portions of the said follower and coin-receiving block whereby in the absence of a coin said arm is adapted to pass freely through between the said parts without effecting their movement.

14. In a coin-controlled machine, the combination with an indicating device, its shaft and a pinion upon the shaft, of a slidable coin-receiving block, vertical rods upon which the same is adapted to move, a rack-rod clamped to said slidable coin-block and adapted to move with it, a spring for holding said coin-block in an elevated position to receive the coin, and devices substantially as herein shown and described and adapted upon the insertion of a coin to actuate said slidable coin-block and the indicating mechanism.

15. In a coin-controlled machine, the com-

bination with an indicating device, its shaft and a pinion upon the shaft, of a slidable coin-receiving block, vertical rods upon which the same is adapted to move a rack-rod clamped to said slidable coin-block and adapted to move with it, a spring for holding said coin-block in an elevated position to receive the coin, devices substantially as herein shown and described adapted upon the insertion of a coin to actuate said slidable coin-block and the indicating mechanism, and a follower above the slidable coin-block and adapted for a limited or predetermined movement upon the descent of the said coin-block and adapted to close off the coin-aperture, substantially as set forth.

16. In a coin-controlled machine, the combination with an indicating device and means associated therewith for actuating the same, of separate manually-operated devices, spring-controlled devices intermediate of the manually-operated devices and actuated by either, and separate independent devices intermediate of the spring-controlled devices and the indicating devices and between which the coin is received, substantially as specified.

17. In a coin-controlled machine, the combination with an indicating device and means associated therewith for actuating the same, of separate manually-operated devices, devices intermediate of the manually-operated devices and actuated by either, and separate independent devices intermediate of the latter devices and the indicating devices and between which the coin is received, substantially as specified.

18. In a coin-controlled machine, a slidable block and vertical guides therefor, said block having a coin way or slide, receiving and down which the coin moves, lugs for arresting a coin of a given denomination, an indicating device, means associated therewith and connected also to the slidable block, and separate independent manually-operated devices adapted to come into contact with the coin and thereby to actuate the slidable block and the parts intervening between the same and the index.

19. In a coin-controlled machine, a slidable block and vertical guides therefor, said block having a coin way or slide receiving and down which the coin moves, lugs for arresting a coin of a given denomination, a device normally resting upon the slidable block and to which is connected the said coin-arresting lug, said device having a vertical face and a limited vertical movement, said face at the end of said movement covering the coin-slot and preventing the insertion of a second coin until the movements have been completed.

20. In a coin-controlled machine, a slidable block and vertical guides therefor, said block having a coin way or slide receiving and down which the coin moves, lugs for arresting a coin of a given denomination, a device normally resting upon the slidable block and to which is connected the said coin-arresting lugs,

said device having a vertical face and a limited vertical movement, said face at the end of said movement covering the coin-slot and preventing the insertion of a second coin until the movements have been completed, an indicating device, means associated therewith for actuating the same, a connection from the latter means to the slidable block, and a spring for returning the parts to their normal position.

21. In a coin-controlled machine, a slidable block and vertical guides therefor, said block having a coin way or slide receiving and down which the coin moves, lugs for arresting a coin of a given denomination, a device normally resting upon the slidable block and to which is connected the said coin-arresting lugs, said device having a vertical face and a limited vertical movement, said device at the end of said movement covering the coin-slot and preventing the insertion of a second coin until the movements have been completed, an indicating device, means associated therewith for actuating the same, a connection from the latter means to the slidable block, a spring for returning the parts to their normal position, and a spring-controlled friction device acting upon the means associated with the indicating device for holding the same at the end of their indicating movements, and which friction devices are manually released to permit the aforesaid spring to return the parts to their normal position.

22. In a coin-controlled machine, a slidable block and vertical guides therefor, said block having a coin way or slide receiving and down which the coin moves, lugs for arresting a coin of a given denomination, a device normally resting upon the slidable block and to which is connected the said coin-arresting lugs, said device having a vertical face and a limited vertical movement, said face at the end of said movement covering the coin-slot and preventing the insertion of a second coin until the movements have been completed, an indicating device, means associated therewith for actuating the same, a connection from the

latter means to the slidable block, a spring for returning the parts to their normal position, a pivoted gravity device adapted to engage said slidable block at its extreme movement and to hold the same and the parts connected therewith and extending to the indicating device for a predetermined period.

23. In a coin-controlled machine, a slidable block and vertical guides therefor, said block having a coin way or slide receiving and down which the coin moves, means for arresting a coin of predetermined denomination, a device over and normally resting upon the slidable block and coacting therewith to receive deposited coins, said device having a limited vertical movement with the initial movement of the slidable block.

24. In a coin-controlled machine, a slidable block having a coin way or slide receiving and down which the coin moves, means for arresting a coin of predetermined denomination, a device over and normally resting upon the slidable block and coacting therewith to receive deposited coins, said device having a limited vertical movement with the vertical movement of the slidable block.

25. In a coin-controlled machine, the combination with an indicating device, and means associated therewith for actuating the same, of a coin-receiving block having divided inclined ways, a follower device also having inclined divided parts, lugs on the under side of one part adapted to act upon a coin of predetermined denomination, manually-operated devices, a spring-controlled rod actuated thereby, an arm extending forward of the spring-controlled rod and entering the notch or space between the divided portions of the said follower and coin-receiving block whereby in the absence of a coin said arm is adapted to pass freely through between the parts without effecting their movement.

Signed by me this 25th day of May, 1903.
